UNITED STATES PATENT OFFICE.

ELMER E. HAUER, OF SPRINGFIELD, OHIO, ASSIGNOR TO THE LAGONDA MANUFACTURING COMPANY, OF SPRINGFIELD, OHIO, A CORPORATION OF OHIO.

ROTARY MOTOR.

1,102,915.

Specification of Letters Patent.

Patented July 7, 1914.

Application filed January 16, 1911. Serial No. 602,786.

To all whom it may concern:

Be it known that I, ELMER E. HAUER, a citizen of the United States, residing at Springfield, in the county of Clark and State of Ohio, have invented certain new and useful Improvements in Rotary Motors, of which the following is a specification, reference being had therein to the accompanying drawings.

10 My invention relates to rotary motors and more particularly to rotary motors employed in driving boiler tube cleaners that are adapted to travel through the tube with the cleaner, although they may be used for other purposes.

15 The object of my invention is to simplify and improve the construction so as to give greater efficiency and to afford better means of lubrication.

20 With these and other objects in view my invention consists of the constructions and combinations hereinafter described and set forth in the claims.

25 In the drawings Figure 1 is a longitudinal section of a rotary motor, taken through the exhaust ports, embodying my invention. Fig. 2 is a longitudinal section taken through the inlet ports. Fig. 3 is cross-section on the line A A of Fig. 1. Fig. 4 is 30 cross-section on the line B B of Fig. 2 and Fig. 5 is cross-section on the line C C of Fig. 1.

Like numerals represent the same parts in the several views.

35 In the drawings 1 represents a casing having a head 2, preferably formed integrally therewith as shown and having exhaust ports 3. Said casing is provided with a sleeve 4 and a wearing plate 5 having exhaust ports 5^a is interposed between said sleeve and exhaust head, a dowel pin 6 holding said sleeve and plate from turning in the casing. A journal block 7 is seated against the opposite end of said sleeve and 40 a dowel pin 8 keeps the same from turning in the casing. Said sleeve is formed with exhaust recesses 9 adapted to register with the exhaust ports 5^a of the wearing plate; and is further provided with inlet recesses 45 10 adapted to register with inlet ports 11 in the journal block 7.

A head 12 is screw-threaded at 13 to the casing and has a reduced portion 14 which bears against the journal block and forms 50 with said journal block and casing an annu-

lar chamber 15 into which the inlet ports 11 of the journal block open in whatever position to which the head 12 may be turned in the casing. Said head extends rearwardly and is made hollow as shown so that 60 when screw-threaded in place it forms with said journal block a lubricant chamber 16. Inwardly extending ribs 17 formed on the walls of the head 12 have inlet ports 18 therethrough leading from a screw-threaded 65 opening 19 in which the supply hose is attached, to the annular chamber 15. A feed hole 20 to supply the lubricant chamber is provided with a hollow plug 21, a ball 22 and a spring 23 to hold said ball in the 70 opening of the plug.

A rotary piston 24 is preferably formed integrally with a shaft 25 which is journaled in the block 7 and head 2, bushings 26 and 27 being preferably provided to 75 form bearings therefor. The forward end of the shaft projects through the head 2 and is screw-threaded at 28 to attach the tool to be driven. The sleeve 4 forms a working chamber of such dimensions that 80 when the piston 24 is mounted therein it will contact the walls of the chamber in two places opposite each other forming two oppositely disposed crescent shaped chambers 29 as particularly shown in Fig. 5. Paddles 30 are seated in recesses 31 of the piston and are adapted to move radially into the chambers 29 in a well known manner.

85 A feed conduit 33 leads from the lubricant chamber 16 to the working chamber and I 90 preferably also provide a cross conduit 34 opening through the bushing 26 to rear journal bearing; and the quantity of lubricant is adjusted by the means of the needle valve 35 seated at the junction of the conduits as shown and operated by a screw-plug 95 36 to which it is attached.

An annular recess in the head 2 abutting the bushing 27 forms a lubricant chamber 37 having openings 38 to the front journal bearing; and a conduit 39 leads from the working chamber to said lubricant chamber 37. It will be seen that the rear bearing and the working chamber are supplied with the desired amount of lubricant; and that the lubricant being mixed with the motive agent also passes to the front bearing.

100 To relieve the pressure of the motive agent at the rear end of the shaft a conduit 40 is provided extending through the piston and 110

shaft, venting through at the end thereof or at the side as shown or in any suitable manner.

I preferably provide a removable cap 32 at the rear end of the journal block 7 so that the bushing 26, when it becomes worn may be readily removed and a new bushing supplied.

Having thus described my invention I claim:—

1. In a rotary motor, a casing and a head therefor having a hollow rearward extension, the circumferential walls of which have inwardly projecting ribs with inlet ports therethrough for the motive agent, substantially as described.

2. In a rotary motor, a casing, a journal block seated therein and a head for said casing having a hollow rearward extension closed at its outer end, the circumferential walls of which form with said closed end and said block a lubricating chamber, said circumferential walls having inwardly projecting ribs with inlet ports therethrough for the motive agent, substantially as described.

3. In a rotary motor, a casing having a working chamber, a journal block seated in said casing and having ports communicating with said working chamber, a head screw threaded to said casing and having a reduced portion of less diameter than the bore of the casing, seated against said block and forming with said block and casing an annular chamber into which said ports open, said head having a hollow rearward extension, closed at its outer end, the circumferential walls of which have inwardly projecting ribs with inlet ports therethrough to said annular chamber, substantially as described.

4. In a rotary motor, a casing having a bearing closed at one end and a piston having a shaft journaled in said bearing, said shaft having a conduit with a free vent opening to the atmosphere to relieve the pressure at the end of the shaft in said bearing, substantially as described.

5. In a rotary motor, a casing having oppositely disposed inlet and discharge ends, a through bearing in said discharge end and a socket bearing in said inlet end, a piston 50 having a shaft journaled in said bearings and projecting through said discharge end, said shaft having a conduit with a free vent opening to the atmosphere to relieve the pressure at the rear end of said shaft, substantially as described.

6. In a rotary motor, a casing having a motor chamber with oppositely disposed inlet and discharge ends, bearings in the respective ends, the bearing at the inlet end 60 being closed except an opening into the motor chamber to receive the motor shaft, a piston with radially moving blades in said chamber and having a shaft journaled in said bearings, said shaft having a conduit 65 with a free vent to the atmosphere to relieve the pressure at the rear end of said shaft, substantially as described.

7. In a rotary motor, a casing having a motor chamber, a head having a hollow extension, front and rear bearings on opposite sides of said chamber, the rear bearing being closed at its rear end and projecting into said head extension, a piston having a shaft projecting through said front bearing and 75 adapted to attach the tool to be driven, the rear end of said shaft terminating within said rear bearing and having a conduit therein giving a free vent from said bearing to the atmosphere in front of the motor, the 80 circumferential walls of said head extension having inwardly extending ribs with ports therethrough communicating with said motor chamber, substantially as described.

In testimony whereof I have hereunto 85 affixed my signature in the presence of two witnesses.

ELMER E. HAUER.
